UNITED STATES PATENT OFFICE.

ANDREW CHRISTIANSON, OF BUTLER, PENNSYLVANIA, ASSIGNOR TO STANDARD MOTOR TRUCK COMPANY, OF PITTSBURGH, PENNSYLVANIA, A CORPORATION OF PENNSYLVANIA.

BOLSTER-HANGER.

1,142,237.

Specification of Letters Patent.

Patented June 8, 1915.

Application filed April 10, 1914. Serial No. 830,914.

To all whom it may concern:

Be it known that I, ANDREW CHRISTIANSON, a citizen of the United States, and resident of Butler, in the county of Butler and State of Pennsylvania, have invented a new and useful Improvement in Bolster-Hangers; and I do hereby declare the following to be a full, clear, and exact description thereof.

10 My invention relates to bolster-hangers for railway-trucks, and more especially motor-trucks employed on electric railways.

The object of my invention is to provide a bolster-hanger which will act to dampen or 15 check the end-swing of the bolster which when allowed to go uncontrolled, makes very uncomfortable riding for the passengers.

To these ends my invention comprises, generally stated, bolster-hangers suspended 20 from the transoms or cross-frame, and carrying curved bearing-blocks or shoes, and the spring supporting members having curved faces contacting with the curved faces of said blocks and resting thereon, 25 whereby there is a friction set up between these two faces which tends to check or retard the swing of the bolster supported on said hangers.

In the accompanying drawing, Figure 1 30 shows a portion of a truck frame with my improved bolster-hanger suspended therefrom, the lower portion of the bolster-hanger and the spring support being shown in section; Fig. 2 is a section taken at right 35 angles of that shown in Fig. 1; Fig. 3 is an enlarged detail; Figs. 4 and 5 are views in modified form; and Fig. 6 is another modified form of my invention.

In the drawing, I have only illustrated 40 the parts of a truck necessary to properly portray my invention, and accordingly the numeral 2 designates the transom or frame connecting the side-frames of a common form of truck. Suspended from the frame 2 45 is the hanger 3 which in this case consists of a U-shaped member formed of one piece of metal bent to this shape. Supported on the lower cross-member 4 of the hanger is the shoe 5 which in this case may consist of 50 a suitable casting, preferably of malleable iron, having the rounded or convex upper-face 6, with the overhanging lug portions 7 which control the lateral movement of said

shoe upon the lower cross-bar 4 of the hanger. The spring-support 8 is riveted or 55 otherwise secured to the spring-plank 9, and said spring-support has the curved concave face 10 which rests in contact with the convex curved face 6 of the shoe 5. The springs 11 rest upon the spring-support 8 and the 60 bolster 12 rests upon said springs.

The end-swing of the bolster is checked by the frictional contact of the face 10 of the spring-support 8 with the curved face 6 of the shoe 5, and in this way I provide a very 65 simple and efficient means for guarding against the undue longitudinal swing of the bolster and the discomfort to the passengers occasioned thereby. The shoe 5 may be readily renewed from time to time and its 70 withdrawal and insertion is a simple matter.

In Figs 3 and 4 I have illustrated a modified form of invention in which the hanger instead of being made of a single piece of metal bent to U-shape, is formed of the arms 75 13 connected by means of the rod or bolt 14. A shoe 15 formed of spring-steel, or other suitable material, is secured to the rod 14 by means of the rivets 16 passing through said rod. The spring-support 16 is 80 formed with the curved recess 17 which engages the shoe 15 and the action in this case will be the same as that above set forth, as the friction created between the two sliding surfaces of the shoe 15 and the curved face 85 17 of the spring support 16 will check the longitudinal swinging of the bolster.

In Fig. 5, I have illustrated another form of my invention, in which the friction shoe 18 is formed integral with the lower cross 90 member of the U-shaped hanger.

By my invention, I provide a simple and efficient form of damping device which is formed at the connection of the hangers with the spring-support, and am enabled to 95 dispense with the damping plates and other devices of a like character which have been generally used heretofore for providing against undue longitudinal swing of the bolster.

100

What I claim is:

1. The combination of a bolster hanger, a shoe supported thereby having a convex frictional face, and a spring-support having a concave frictional face engaging said first 105 named frictional face.

2. The combination of a bolster-hanger, a
shoe resting on the cross member of said
hanger having an overhanging portion, said
shoe having a convex frictional face, and a
5 spring-support having a concave frictional
face engaging said first named frictional
face.

In testimony whereof, I the said ANDREW
CHRISTIANSON have hereunto set my hand.

ANDREW CHRISTIANSON.
